CARRIER RACK FOR TUMBLERS

Morton Ocuin, 2736 Independence Ave.,
New York, N.Y. 10463

Filed Sept. 18, 1972, Ser. No. 290,254

Term of patent 14 years

Int. Cls. D9—03; D7—99

U.S. Cl. D7—71

FIG. 1

FIG. 2

FIG. 3

FIG. 4

FIG. 1 is a top plan view from above of a carrier rack for tumblers showing my new design;

FIG. 2 is a front elevational view thereof;

FIG. 3 is an end elevational view thereof; and

FIG. 4 is a bottom plan view thereof.

The side or rear opposite that shown in FIG. 2 is a mirror image of the side shown.

I claim:

The ornamental design for a carrier rack for tumblers, as shown and described.
